Design U.S. Appl. No. 29/425,968, filed Jun. 28, 2012; Inventors: Holloway, Choi, LaRusso, and Guers-Neyraud.

Primary Examiner — Dominic Simone

(74) Attorney, Agent, or Firm — Fross Zelnick Lehrman & Zissu, P.C.; Lawrence E. Apolzon, Esq.

(57) CLAIM

The ornamental design for footwear, as shown and described.

DESCRIPTION

FIG. 1 is a front perspective view of a shoe showing my footwear design;

FIG. 2 is a left side view of the footwear shown in FIG. 1; FIG. 3 is a right side view of the footwear shown in FIG. 1; FIG. 4 is a front view of the footwear shown in FIG. 1; FIG. 5 is a rear view of the footwear shown in FIG. 1; and, FIG. 6 is a top view of the footwear shown in FIG. 1. The broken line showing of the sole, heel, zipper, portion of the footbed, heel cap, and portion of the heel cup, are for illustrative purposes only and form no part of the claimed design.

1 Claim, 6 Drawing Sheets
